UNITED STATES PATENT OFFICE

JOHN JORGENSEN, OF RACINE, WISCONSIN, ASSIGNOR OF ONE-HALF TO MICHAEL JORGENSEN, OF RACINE, WISCONSIN

CYLINDER FOR LAUNDRY MACHINES

Application filed November 5, 1926. Serial No. 146,399.

This invention relates to improvements in cylinders for laundry machines.

It is one of the objects of the present invention to provide a laundry machine cylinder of a sectional, knock-down construction.

A further object of the invention is to provide a laundry machine cylinder which is very simple to assemble and in which the 10 various parts are readily replaceable.

A further object of the invention is to provide a metal wash cylinder in which the various units are of a uniform size and may be used in a cylinder of a desired length and 15 with any number of pockets, the units being adapted for either a closed or an open type of washer.

A further object of the invention is to provide a cylinder of the class described of a 20 jointed construction, whereby the units are easily and securely assembled to form a smooth, flush surface.

A further object of the invention is to provide a cylinder of the class described which 25 is of a unique construction and formed with inside supporting bands.

A further object of the invention is to provide a metal wash cylinder in which all of 30 the parts are cast and in which no machine work is required.

A further object of the invention is to provide a laundry cylinder in which all of the plates making up the outer shell are formed 35 with alternating and reversed notches or recesses and tongues or projections offset and cast in such a way that the members interlock to form a secure joint.

A further object of the invention is to 40 provide a sectional laundry cylinder which can be made up with the same rib and plate castings into cylinders of different lengths and diameters.

A further object of the invention is to 45 provide a sectional laundry cylinder, which because of the character of the constituent parts, enables a dealer to keep a large stock in a very compact way in a limited space, facilitates and simplifies packing and shipping, eliminates possibility of errors in as-

sembling and does not require the use of special tools or jigs in assembling.

A further object of the invention is to provide a cylinder of the class described which is of very simple construction, is 55 strong and durable and is well adapted for the purposes described.

With the above and other objects in view, the invention consists of the improved laundry machine cylinder, and its parts and combinations as set forth in the claims, and all equivalents thereof.

In the accompanying drawings in which the same reference characters indicate the same parts in all of the views:

Fig. 1 is a perspective view of the improved laundry machine cylinder;

Fig. 2 is a cross-sectional view thereof, taken on line 2—2 of Fig. 1, and on a larger scale;

Fig. 3 is an enlarged detail plan view of a plate used in the cylinder looking at the outer surface thereof;

Fig. 4 is a sectional view taken on line 4—4 of Fig. 1 and on a larger scale;

Fig. 5 is a fragmentary detail perspective view of a rib;

Fig. 6 is a perspective view of a modified form of cylinder;

Fig. 7 is an end view thereof and on a 80 larger scale;

Fig. 8 is an enlarged detail view of the strap or support member;

Fig. 9 is a fragmentary edge view of a plate used in the cylinder showing the 85 tongue and notch arrangement;

Fig. 10 is a fragmentary plan view of a plate showing the inner surface thereof, and

Fig. 11 is a cross-sectional view of the plate shown in Fig. 10.

Referring now more particularly to the drawings, it will appear that the cylinder comprises a pair of end heads 10 joined by longitudinally extending spaced-apart ribs 11. Also, a plurality of intermediate heads 12 divide the interior of the cylinder into a plurality of compartments or sections. It will be noted that the peripheries of the heads are formed with U-shaped recesses 13 100

to accommodate the ribs 11, the ribs being bolted thereto, as shown in Fig. 2.

A rib 11 is shown in detail in Fig. 5 and the same is U-shaped in cross section, and its walls are formed with a plurality of apertures 14. The outer edge portions of the side walls of each rib are also formed with recesses 15 to form joints.

The periphery of the cylinder, except for certain portions reserved for doors, is covered by a plurality of curved plates 16, shown in detail in Figs. 3, 9, 10 and 11. The edge portions of said plates are provided with alternating and reversed recesses 17 and tongues 17' by which means the plates are secured together to form half lap joints and to the ribs 11, as shown in Fig. 1. The plates are also secured by bolts 18 to the rim portions of the heads 10 and 12.

Said plates are cast with a plurality of suitably sized and spaced perforations 19. As shown clearly in Figs. 10 and 11, the perforations 19 are tapered to form funnel-shaped openings, being larger on the inside of the cylinder. It will also be noted that the tapers of the different perforations are graduated from the center outwardly toward both side edges of the plate. That is to say, the outermost walls of the holes outwardly of the medial portion of the plate are more tapered than those toward the center of the plate, as indicated at 19'. The arrangement of said perforations is such that water may enter the cylinder with reduced resistance and when clothing within the cylinder strikes the openings, the water is readily drained therefrom and the tapered formation of the openings causes them to act in the manner of scoops when the cylinder is reciprocated.

The compartments within the cylinder are divided by diametrically extending shelves 20 flanged at their edge portions and bolted to the plates 16 and to the heads 12. Said shelves are also provided with spaced perforations 21.

The surface of the cylinder is arranged with opposed door openings to afford access to the compartments or pockets, and said openings are adapted to be controlled by doors 22. Said doors are slidably mounted between outer strips 23 and inner strips 24 held together by screws 25. Each door is provided with perforations, and is releasably retained in closed position by a single lock or catch 26 mounted on the adjacent rib 11.

It will thus be seen that the cylinder, illustrated by Figs. 1, 2, 3, 4 and 5, is of the closed type of cylinder washer, and is composed primarily of heads, ribs and plates suitably jointed together, the units being arranged for quick assembly and the ready replacement of parts.

In Figs. 6, 7 and 8, an open type of cyl-

inder has been illustrated, wherein end heads 10' are provided and are connected together by longitudinal ribs 11 of U-formation. The rim of the heads 10' is formed in a plurality of sections 27, one of which is shown in detail in Fig. 8, and said sections are bolted together and to the ribs, as in Fig. 7. Plates 16, jointed together and to the ribs 11, form the outer surface of the cylinder except at one portion where door openings are provided. The openings are controlled by doors 22' slidably mounted between strips, as in the main form of the invention, and releasably held in closed position by locks 26.

The interior of the cylinder, in this form of the invention, is entirely open and uninterrupted. However, the members are braced at intermediate points by sections 27 bolted to the ribs 11 and to the plates 16 where they contact with the same.

From the foregoing description, it will be seen that the improved cylinder for laundry machines is of very simple and novel construction, and is well adapted for the purposes described.

What I claim as my invention is:

1. As a new article of manufacture, a plate for reciprocating cylinders having a plurality of tapered openings, the tapers of said openings being graduated as to inclination toward the side edges of the plate, to act on a liquid when the plate is moved, the metal adjacent the openings being non-protruding so that the plate surfaces are smooth.

2. A laundry machine cylinder, comprising a plurality of heads, the periphery of said heads being formed with U-shaped recesses, ribs, U-shaped in cross-section, connecting said heads and detachably mounted in said recesses, the edge portions of the ribs being formed with tongues and grooves, and a plurality of perforated, curved plates interposed between the ribs, the side edges of said plates being formed with alternating tongues and recesses for engagement with adjacent rib tongues and recesses, and some of said tongues and recesses engaging the tongues and recesses of adjacent plates.

3. In a knock-down laundry machine cylinder, a sectional frame consisting of heads and ribs connected together, and a wall composed of sheets having detachable tongue and groove joint connections with each other and with the ribs, there being a longitudinal joint between a pair of sheets intermediate a pair of ribs.

In testimony whereof, I affix my signature.

JOHN JORGENSEN.
